APPLICATION OF FRENCH BINDING

Philip L. O'Donnell, Cincinnati, Ohio, assignor to
James B. O'Donnell, Cincinnati, Ohio

Application February 10, 1933, Serial No. 656,129

3 Claims. (Cl. 12—146)

This invention relates to the shoe working art and particularly to means and method for attaching the tape to the edges of shoe uppers. However, the invention is likewise applicable to uses other than shoe making in which the attachment of tape to material, or the union of two materials, is the objective. The present disclosure is a further development of that set forth in my co-pending application Serial No. 497,092. As 10 in the previous disclosure, the particular attachment of the tape contemplated is known as French folding and the machine conventionally illustrated in the accompanying drawing is of the type which effects such a fold.

15 An object of the invention is to provide improved means and method for effecting adhesion of adhesively coated tape to a shoe upper or other flexible material.

Another object is to provide means of this kind 20 in which the use of heat for effecting a proper adhesive state of the tape is obviated.

Another object is to provide means for eliminating movable adhesive applicators now commonly in use in the shoe working and related 25 arts.

Another object is to achieve these results with means simple in manufacture and use and efficient in operation.

These and other objects are obtained by the 30 means described herein and illustrated in the accompanying drawing in which:

Fig. 1 is a side elevational view representing conventionally a French folding machine with the means of the present invention attached thereto, parts being shown in cross section.

Fig. 2 is a view taken on line 2—2 of Fig. 1.

Fig. 3 is a view taken on line 3—3 of Fig. 2, the bottom edge of a positioned shoe upper or the like being turned outwardly to disclose a French 40 fold.

Fig. 4 is a fragmental detail view of partially coated tape which may be utilized in the same way as the fully coated tape shown in Fig. 3.

The present invention is designed to overcome 45 the difficulty of effecting a permanent attachment of the tape to the edge of shoe uppers. The use of a brush or the like for dampening the adhesively coated side of tape immediately before application thereof, has commonly been the practice in 50 the past and found to be a slow and tedious method. Moreover, the dampening is not always effected smoothly and evenly on the coated surface so that certain portions did not adhere properly upon the subsequent application of pressure. 55 Another method commonly followed heretofore

has been the heating of the adhesive tape immediately before it is positioned upon the leather. The maintenance of the proper degree of heat for the purpose required was difficult and involved expensive and complicated mechanism. The 5 present invention overcomes difficulties of this kind by providing means for spraying the coated side of the tape, and if desired the surface of the shoe upper adjacent thereto, immediately before folding and pressing down of the tape. This 10 spraying is accomplished by the use of a tank or the like containing the liquid to be sprayed, ordinarily water, said tank being provided with air pressure and aerating means for discharging the liquid through an outlet tube onto the tape and 15 material at the time indicated.

With reference to the drawing: The French folding machine conventionally illustrated comprises a body 5 supporting a pair of spaced lateral arms 6 and 7 disposed one above the other in 20 parallelism. The operating mechanism of the machine is indicated by the pulley 8 and belt 9. The arm 6 is provided at its outer end with a shuttle which moves the leather across said arm in the manner of a sewing machine. The arm 7 25 has attached thereto portions of the mechanism, conventionally represented and comprising a supporting arm 10 which has the knurled roller 22 upon its outermost end, said roller serving to retain the shoe upper in proper position in its 30 movement across the shuttle. Intermediate the end of arm 10 the guide finger 11 is adjustably disposed, said finger serving to properly retain the unfolded tape in position for the subsequent folding operation. The arm 6 which is hollow has the 35 forked folding finger 23 associated therewith, said finger being disposed adjacent the finger 11 and being reciprocated by suitable mechanism transversely of the edge of the shoe upper for folding the tape. A hammer 24, the operation of which 40 is subsequent to that of the folding finger 23, is likewise associated with the arm 6. Hammer 24 applies pressure to the folded tape for assuring its permanent attachment. Adjacent the body 5 of the machine an electric motor 12 and air compressor 13 is positioned. Upon the top of body 5 a supply tank or container 14 is attached. The container 14 and compressor 13 are connected by a communicating pipe or conduit 15 by which air under pressure is supplied interiorly of container 50 14. Inside of the container a stub pipe 16 provides a continuation of the conduit 15, and has at its free end an attachment 17 by which air is emitted in two directions within the container as indicated by the small arrows in Fig. 1. At the 55

bottom of the container adjacent the attachment 17 a port 18 is provided from which exteriorly of the container a pipe 19 extends, said pipe having a suitable supporting bracket as indicated at 20. 5 Pipe 19 is preferably semi-rigid so that its free end 21 may be disposed in a desired position relative to the work being operated on by the folding mechanism.

It is to be understood that one edge of the tape 10 25 is stitched, previous to the operations herein contemplated, to the outer face of a shoe upper 26. These joined members are then positioned upon arm 6 with the stitched edge of the tape turned down and the main portion thereof extending 15 beyond the edge of the shoe upper as seen in Figs. 2 and 3. The guide finger 11 serves to raise the tape into an angular position relative to the shoe upper 26, (Fig. 3) and it is at this point, adjacent one edge of arm 6, that the end 21 of pipe 20 19 is positioned for applying the liquid to the tape and to the adjacent portion of the shoe upper. The end 21 is preferably flattened for effecting a greater dispersion of the adhesive liquid and likewise to assist in the vaporous or 25 semi-vaporous ejection thereof.

The pressure of air entering container 14 is directed upwardly through the liquid in opposite or divergent directions as indicated by the arrows (Fig. 1). A pressure of air is thus built up, between the top surface of the liquid and the top 30 of the container, and at the same time a churning and constant movement of the liquid in the container is effected whereby precipitation and adherence of the liquid to the interior of the container, is precluded. The liquid, mixed with air, 35 is ejected through port 18 into pipe 19, in which a valve 21, for controlling the flow, is positioned. The ejection, in a vaporous or spray condition, of the aerated liquid from pipe end 21 results in effectively dampening the adhesive or glue coating 30 of the tape and, by slight adjustment of 40 said pipe end, the adjacent portions of the shoe upper so that subsequent folding and pressing operations result in firm and permanent adhesion 45 of the tape to the material. As previously

suggested, the tape need not be fully coated as illustrated in Figs. 1, 2 and 3. The tape 31 provided with a partial coating 32 is illustrated in Fig. 4. It is obvious that the uncoated edge of this kind of tape is initially stitched to the leather 5 and that the coated portions are then operated upon in the manner heretofore described. It is obvious that other kinds of tape are equally adaptable for use in the present invention such, for example, as tape having its longitudinal edge 10 or edges pinked. Modifications suggest themselves upon considering the means herein set forth but these are believed to be comprised in the spirit and scope of the present invention. 15

What is claimed is:

1. The method of joining adhesively coated tape to the edge portion of a shoe upper, comprising attaching an edge of the tape to an edge of the upper, turning the tape, coated side up, into angular relationship with the upper substantially less than 180 degrees, spraying the coated side of the tape and adjacent surface of the upper with a liquid mist, and pressing said surfaces together to effect adhesion thereof. 25

2. The method of joining adhesively coated tape to the edge portion of a shoe upper, comprising attaching an edge of the tape to an edge of the upper, turning the tape, coated side up, into angular relationship with the upper substantially less than 180 degrees, spraying the coated 30 side of the tape with a liquid mist, and pressing said coated side against the adjacent surface of the shoe upper.

3. The method of joining adhesively coated tape to the edge portion of a shoe upper, comprising attaching an edge of the tape to an edge of the upper, disposing the coated side of the tape in such position as to be folded over the edge of the upper and onto a surface thereof by a turn of substantially less than 180°, spraying 40 with liquid the coated side of the tape, and folding the sprayed side of the tape over the edge and against the adjacent face of the upper.

PHILIP L. O'DONNELL. 45
